G. COWLES

HOT WATER HEATER

Filed Aug. 2, 1921

Fig. 1.

Fig. 2.

*Inventor
George Cowles
By Chas E. Townsend*

Attorney

UNITED STATES PATENT OFFICE.

GEORGE COWLES, OF SACRAMENTO, CALIFORNIA.

HOT-WATER HEATER.

Application filed August 2, 1921. Serial No. 489,163.

To all whom it may concern:

Be it known that I, GEORGE COWLES, a citizen of the United States, residing at Sacramento, in the county of Sacramento and State of California, have invented new and useful Improvements in Hot-Water Heaters, of which the following is a specification.

This invention relates to a water heater, and particularly pertains to a coil manifold therefor.

The present invention is concerned with a water heater in which a plurality of spiral water circulating coils are in communication with a single induction manifold and a single eduction manifold; and it is a principal object of the present invention to provide a convenient structure embodying the door frame of the heater and the induction manifold.

The present invention contemplates the use of a door frame, one of the vertical posts of which is formed to provide an induction manifold with which a plurality of circulating coils are in communication. The invention is illustrated by way of example in the accompanying drawing in which

Fig. 1 is a view in side elevation showing the present invention and with parts broken away to more clearly disclose the application of the present invention;

Fig. 2 is a view in transverse section through the heater, as seen on the line 2--2, Fig. 1, further showing the construction.

Referring more particularly to the drawing, 10 indicates an outer cylindrical casing of a hot water heater. Mounted in the bottom of this casing is a gas burner 11, while 40 the upper end of the casing is formed with a flue opening 12 through which the products of combustion from the burner may pass. The front of the heater is provided with a swinging door 13. This door is mounted on a vertical hinge rod 14 by lugs 15. The hinge rod is supported from the door frame 16 with which the present invention is particularly concerned. This frame has parallel vertical portions 17 and 18, and transverse horizontal portions 19 and 20. The portions 17, 19 and 20 are of common design to form a door opening, while the post 18 of the door frame is enlarged and forms a manifold passageway 21, as more clearly indicated in Fig. 2 of

the drawing. This post is substantially cylindrical in formation and is tubular. A continuation of the post forms a lip 22 against which the edge of the door 13 may rest when the door is closed. This lip portion is, of course, in suitable alignment with the outer face of the remainder of the door frame, so that a tight seal will be made between the door frame and the door. A plurality of tapped openings 23 are formed through the wall of the door post 18 and are in communication with the manifold passageway 21. These tapped openings receive the threaded pipes 24 of the various heating coils 25.

By reference to Fig. 1 of the drawing it will be noted that a plurality of superposed spiral heater coils are provided, each of said coils being connected with their respective pipes 24 by a pipe union 26, while the inner ends of the coils are in communication with an eduction pipe 27 through which the heated water will circulate.

It will thus be seen that the present invention provides simple and a compact means whereby heater coils may be placed in communication with an induction manifold, which manifold is conveniently embodied within the structure of the door frame of the heater.

While I have shown the preferred form of my invention, it is to be understood that various changes may be made by those skilled in the art without departing from the spirit of my invention.

Having thus described my invention, what I claim and desire to secure by Letters Patent is:

1. A hot water heater comprising an outer casing having a door opening formed therein, a plurality of circulating coils in the casing, and accessible through said openings, a one piece door frame secured around the marginal edge of said opening, a door hinged to the frame to close the opening, and a water distributing manifold formed as a part of said door frame and separably connected to each of said circulating coils.

2. A hot water heater comprising an outer casing; water circulating coils therein, said casing being formed with an opening in the side thereof to permit access to all of the coils; a door frame circumscribing said opening; a door hinged to one side of the opening for closing the same; and a water

distributing manifold embodied in the opposite side of the frame to communicate with the circulating coils.

3. A water heater comprising an outer cylindrical housing; a plurality of separate circulating coils enclosed thereby and disposed in superposed relation to each other, said housing being formed with an opening in the side wall thereof affording access to the coils; a door frame circumscribing said opening; a door hinged to one side of said frame; and a water induction manifold embodied in the opposite side of the door and with which the various coils communicate. 15
5. In a water heater having an outer casing; a door frame comprising a one-piece rectangular member; lugs formed along one vertical post of said frame; a door hinged thereto; a water manifold embodied within the opposite vertical post of said frame; means for connecting a water supply pipe to the end of said manifold; and means for connecting the manifold with the coils of the water heater. 20

GEORGE COWLES.
